US0D1050568S

(12) **United States Design Patent** (10) Patent No.: **US D1,050,568 S**
(45) Date of Patent: ** Nov. 5, 2024

(54) **CASE FOR CHARGING AN AEROSOL GENERATOR**

(71) Applicant: **Nicoventures Trading Limited**, London (GB)

(72) Inventors: **Kang Min Kim**, London (GB); **Andy Vernal**, London (GB); **Ali Gallaher**, London (GB); **Jared Aller**, Winston-Salem, NC (US)

(73) Assignee: **NICOVENTURES TRADING LIMITED**, London (GB)

(**) Term: **15 Years**

(21) Appl. No.: **29/809,087**

(22) Filed: **Sep. 24, 2021**

(30) **Foreign Application Priority Data**

Mar. 24, 2021 (EM) 008473011-0017

(51) LOC (14) Cl. **27-02**

(52) U.S. Cl.

USPC **D27/162**

(57) **CLAIM**

The ornamental design for a case for charging an aerosol generator as shown and described.

DESCRIPTION

FIG. 1 is a top, front, left perspective view of a case for charging an aerosol generator showing the claimed design; FIG. 2 is a bottom, front, right perspective view thereof; FIG. 3 is a top view thereof; FIG. 4 is a bottom view thereof; FIG. 5 is a front view thereof; FIG. 6 is a rear view thereof; FIG. 7 is a left view thereof; and, FIG. 8 is a right view thereof.

The broken lines consisting of evenly spaced dashes in the drawings depict portions of the case for charging an aerosol generator that form no part of the claimed design; The broken lines consisting of short and long dash lines in the drawing represent boundaries of the design and form no part thereof.

1 Claim, 8 Drawing Sheets
